No. 853,633.

PATENTED MAY 14, 1907.

E. GURRY.

MACHINE FOR FORMING PIG IRON MOLDS.

APPLICATION FILED JUNE 28, 1906.

UNITED STATES PATENT OFFICE.

EDWARD GURRY, OF HAMILTON, ONTARIO, CANADA.

MACHINE FOR FORMING PIG-IRON MOLDS.

No. 853,633.

Specification of Letters Patent.

Patented May 14, 1907.

Application filed June 28, 1906. Serial No. 323,765.

To all whom it may concern:

Be it known that I, EDWARD GURRY, a subject of the King of Great Britain, and residing at Hamilton, in the county of Wentworth and Province of Ontario, Canada, have invented certain new and useful Improvements in Machines for Forming Pig-Iron Molds, of which the following is a specification.

- 10 My invention relates to improvements in machines for molding pig-iron in which a carriage is adapted to travel on a permanent and stationary incline track, or stationary parallel rails, a sand floor between the rails, 15 and a transverse rotary roller of spiral form with a series of flanges, journaled in the carriage, and on the sand, and means for loosening and preparing the sand in advance of the roller.
- 20 The objects of my invention are, first, to provide a machine adapted to run on a stationary and incline track and over a floor of sand, to prepare the sand and to form an incline channel inside of the track and parallel 25 therewith, for the floor of molten iron in the channel, second, to form a succession of level sand floors, third, means for molding sows, or feed passage ways, in the level sand floor, and from the channel and at right angles 30 with the channel, at predetermined distances apart, fourth, to provide means for making level pig-iron molds in the leveled sand on each side of the sow feed passage, and extending therefrom at right angles thereto.
- 35 I attain these objects by the mechanism illustrated in the accompanying drawing, in which:—

Figure 1 is a plan of the machine on the stationary inclined track and having traveled 40 a distance on the track, showing the channel on the left hand side, the transverse feed-passages from the channel, the transverse bank of sand and the pig-iron molds extending from each side of the feed-passage and 45 from each side of the bank of sand. Fig. 2 is a sectional side elevation through the part of the spiral roller between the spiral pig-iron mold formers thereof, the level formed sand floors, and the inclined track, 50 and as viewed from the right-hand side of Fig. 1, of the drawing. Fig. 3 is an enlarged side elevation of a section of the spiral roller and spiral pig-iron mold former partially around the same. Fig. 4 is an enlarged sec- 55 tional elevation of Fig. 3, of the drawing, and

Fig. 5 is an enlarged front elevation of the left-hand part of the spiral roller with three of the number of the spiral mold formers.

Similar letters refer to similar parts throughout the several views. 60

In the drawing the stationary rails of the track are indicated by A, and are on an incline and of any desired length. The upper or higher end part of the track may be for convenience placed in proximity with an 65 iron melting furnace or cupola. One of the rails A, is provided with a lower toothed rack B, on the inner side thereof and stationary therewith.

C, is the carriage which connects the rails 70 A, and has flanged wheels D, which are secured to the ends of the transverse shafts E. The shafts E, are loosely journaled in the carriage C. The right-hand side track wheels D are provided with spur wheels F which 75 form a part of the wheels D, and gears into the stationary spur rack B to give positive motion to the carriage, and also to act as flanges for the wheels D, to guide the same on the track, similar to the inner flanges D' on 80 the opposite similar track wheels D. The fore end part of the carriage C has a transverse shaft H, loosely journaled therein, and the right-hand end of the shaft has a spur wheel J, secured thereto, and which gears into the 85 foremost spur wheel F. The shaft H is provided with a number of fingers K, which revolve together with their shaft when the carriage travels on the track, and in an opposite direction to the shafts E. The fingers K of 90 which there may be an appropriate number, prepare the sand floor preparatory to, and in advance of the spiral formed roller M. The roller M, is for convenience of structure, made in sections, and the dividing line of 95 each section is denoted by 2, and each said section 2, has a centrally located square hole 3, to fit onto the square transverse shaft N, which has round ends to loosely journal in the carriage C. All the said shafts E, H and 100 N, are parallel with each other and revolve together when the carriage C travels.

On the left-hand end of the shaft N, is a channel former P, which is adapted to revolve loosely on the rounded end part of the 105 shaft, and independently of the shaft. The intervening part 4, of the roller M, between the channel former P, and the first section M of the roller, is conical, the largest diametrical part thereof being next to the roller. The 110

conical part 4, has also a central square hole identical with the square holes of the sections of the roller, and revolves therewith together with the shaft. Referring to all the similar sections which comprise the spiral roller M, and which is clearly shown in Figs. 3 and 4 of the drawing, are, when together, parallel and form a continuous roller with spiral pig iron mold formers T.

10 The upper part of the roller M, together with the collars, or flanges T, partially around the same as formers of pig iron molds, and as shown in Fig. 3 of the drawing, has a flared groove 5, which extends from end to end of the roller, and divides the flanges T. The groove 5 forms a transverse bank of sand 6, on the sand floor W, as shown in Fig. 1 of the drawing.

15 The groove 5 is shown on the top part of the roller in all the views of the drawing. The roller M from the bottom of the groove 5 is the nearest part of the roller to the center of the shaft N of the roller, and the top of the groove 5 of the roller is the greatest distance 20 of the roller from said center of shaft, the roller gradually widening outward in spiral form between the two parts referred to and shown in Fig. 3 of the drawing. The flanges T of the roller follow in parallel form the 25 exact contour of the roller and extend therefrom the same distance in the same spiral form as the roller, as shown in said Fig. 3 of the drawing. The lower part of the roller has a bar 8 rounded on its outer parts and 30 which extends from end to end of the roller and continues on the conical part 4, of the roller. The bar 8 is to form the sow or transverse feed passage 9 in the sand at every revolution of the barrel M. The flange T, at the 35 bar 8 is divided and apart to form an opening 10 in the flanges T, one side of said opening being the commencement of the mold or formation of the mold in the sand and the opposite side of the opening is the termination of 40 said mold. It will be noticed that the bar 8 does not project from the barrel M, as far as the flanges T, this feature is to facilitate the 45 complete running off of the molten metal from the sow 9 and into the pig iron molds 12 in the sand and shown in Fig. 1 of the drawing.

50 The flanges T in every operation form the pig-iron molds 12, in the level sand W, which is formed and leveled by the roller M. The 55 pig-iron molds 12, are the same depth and breadth of the flanges T, and the length of the molds are the same as the length of said flanges T from the groove 5, to the opening 10.

50 It will be noticed that the spiral form of the barrel M varies the same as the incline of the track A in the same length of track and circumference of the barrel, in order to roll the sand floor level as shown in Fig. 2 of the drawing. The level of the floor is important, 65 so is the level of the pig-iron molds 12 which

are formed level by the spiral form of the flange T. As the carriage C travels downward on the track the barrel M, together with its number of flanges T decrease in radial line from the center of the shaft N, thereby producing a level sand floor, and level pig-iron molds.

70 One end of the pig-iron molds adjoin the transverse sand bank 6, which is formed in the sand floor by the dividing slot 5, in the barrel, and the opposite ends of said molds adjoin and communicate with the transverse sow, or passage 9, which is formed in the sand floor by the bar 8, and the opening 10, in the flanges T, of the barrel.

75 The channel former P, referred to, forms the channel 13, which is parallel with the track A, and on the same incline as the track and the upper end part of the channel 13 receives the molten iron from a cupola, or iron 80 melting furnace and runs down the channel 13.

85 When the molds are formed in the sand floor, as described, there is a parallel bank of sand 15 formed between the channel 13 and the transverse feed passages 9, and extends 90 the length of the travel of the roller, and opposite to each said formed feed passage the sand is removed by hand, in order to make a passage 16, in the sand floor to connect the channel 13 with the feed passages 9.

95 The operation of the machine is as follows: The carriage C is placed in position on the higher end of the track A, and when brought down grade on its carrying track wheels D, the shaft H and its fingers K revolve together by means of the spur wheels F and J on their shafts E and H respectively. The fingers K prepare the sand floor W, in advance of the roller M, which rolls on the prepared floor at the same time and levels the 100 floor as shown in level lines W in Fig. 2, of the drawing. At this time the independent channel former P, rolls on the floor and forms the channel 13, and the flanges T of the roller M, form the pig-iron level molds 12 on each side 105 of the bank of sand 6 and disconnected from said bank, and the opposite ends of the level molds 12, connect with the sow or feed passage which is formed by the bar or extension 8 of the roller and the openings 10 of the flanges T. The molten iron passage 16 from the channel 13 to the feed passages 9 is formed by hand. The molten metal when poured 110 into the upper end part of the channel 13 runs therein and passes through the passage 16 and thence into the pig-iron molds 12. Each pig-iron when molded is separated and 115 the ends of said irons are easily broken when cooled from the sow 9.

120 What I claim as my invention and desire to secure by Letters Patent is:—

1. In a machine for forming pig-iron molds, an incline track, a carriage adapted to run on the track, a transverse shaft journaled in the carriage, a spiral formed roller on the 130

shaft and adapted to roll level floors of sand by the travel of the carriage, a channel former near to one end of the shaft, means on the roller to form a transverse bank of sand, 5 means on the roller to form a transverse feed passage and means on the roller to form molds for pig-iron on the sides of the feed-passages and communicating therewith.

2. In a machine for forming pig-iron molds, an incline track, a carriage adapted to run on the track, a roller journaled in the carriage and adapted to roll the sand floor to a level plane by the travel of the carriage, and means on the roller to form level pig-iron 15 molds.

3. In a machine for forming pig-iron molds, a track with downward grade, a carriage adapted to travel on the track, a roller journaled in the carriage to roll a sand floor 20 on a level plane by the travel of the carriage, and means on the roller to produce pig-iron molds.

4. In a machine for forming pig-iron molds, a track of downward grade, a carriage 25 adapted to travel on the track, a roller journaled in the carriage and adapted to roll a sand floor on a level plane by the travel of the carriage, means on the roller to form pig-iron molds in the same plane, and means on

the roller to form feed passages to the ends of 30 the molds.

5. In a machine for forming pig-iron molds, an incline track, a carriage adapted to run on the track, a roller journaled in the carriage and adapted to roll the sand on a 35 level plane by the movement of the carriage, means on the roller to form pig-iron molds in the sand and in the same plane, means on the roller to form a transverse feed passage to the molds, means on the roller to form a bank 40 of sand at the opposite ends of the molds, and means on the carriage in advance of the roller to prepare the sand floor.

6. In a machine for forming pig-iron molds, a spiral formed rotary roller adapted 45 to roll and travel on an incline, to roll sand on a level plane, a number of spiral molds, or flanges, extending from the roller and following the same spiral contour, and means extending on the roller and between the molds 50 thereof to form a feed passage or sow, in the sand, to communicate with said molds.

In testimony whereof I affix my signature in presence of two witnesses.

EDWARD GURRY.
